UNITED STATES PATENT OFFICE.

FRANK SCHNEIDER, OF BUFFALO, NEW YORK.

DESIGN FOR A GOBLET OR SIMILAR ARTICLE.

53,319.

Specification for Design.

Patented May 13, 1919.

Application filed February 17, 1919. Serial No. 277,666. Term of patent 7 years.

To all whom it may concern:

Be it known that I, FRANK SCHNEIDER, a citizen of the United States, residing at Buffalo, in the county of Erie and State of New York, have invented a certain new, original, and ornamental Design for a Goblet or Similar Article, of which the following is a specification, reference being had to the accompanying drawings, forming part thereof, in which:

Figure 1 is a side elevation of a goblet showing my design.

Fig. 2 is an elevation of the reverse side from that shown in Fig. 1.

Fig. 3 is a section taken on line 3—3, Fig. 1, looking up.

I claim:

The ornamental design for a goblet or similar article, as shown.

FRANK SCHNEIDER.
